US00D965526S

(12) **United States Design Patent** (10) Patent No.: **US D965,526 S**
(45) Date of Patent: **** Oct. 4, 2022**

(54) **COMBINED DAMPER AND VALVE ACTUATOR**

(71) Applicant: **BELIMO Holding AG**, Hinwil (CH)

(72) Inventor: **Walter Jungen**, Adliswil (CH)

(73) Assignee: **BELIMO HOLDING AG**, Hinwil (CH)

(**) Term: **15 Years**

(21) Appl. No.: **35/510,174**

(22) Filed: **Feb. 28, 2020**

(80) **Hague Agreement Data**

Int. Filing Date: **Feb. 28, 2020**

Int. Reg. No.: **DM/207523**

Int. Reg. Date: **Feb. 28, 2020**

Int. Reg. Pub. Date: **Aug. 28, 2020**

(30) **Foreign Application Priority Data**

Nov. 27, 2019 (CH) 145038

(51) LOC (13) Cl. **13-03**

(52) U.S. Cl.

USPC **D13/123**

(58) **Field of Classification Search**

USPC D13/123, 174, 180, 112, 133, 101;
D23/233

CPC H02N 2/101

(57) **CLAIM**

The ornamental design for a combined damper and valve actuator, as shown and described.

DESCRIPTION

1. Combined damper and valve actuator

1.1 : Right

1.2 : Left

1.3 : Back

1.4 : Front

1.5 : Top

1.6 : Bottom

1.7 : Perspective

1.8 : Perspective

The broken lines shown in 1.3 depict portions of the article and form no part of the claim.
